UNITED STATES PATENT OFFICE.

HARRY J. HICK, OF ALLIANCE, OHIO, ASSIGNOR, BY MESNE ASSIGNMENTS, TO THE
MCASKEY REGISTER COMPANY, (INCORPORATED IN 1914,) OF ALLIANCE, OHIO, A
CORPORATION OF OHIO.

FILING APPLIANCE.

1,118,007.

Specification of Letters Patent. Patented Nov. 24, 1914.

Application filed February 23, 1910, Serial No. 545,560. Renewed March 28, 1914. Serial No. 828,094.

To all whom it may concern:

Be it known that I, HARRY J. HICK, a citizen of the United States, residing at Alliance, in the county of Stark and State of Ohio, have invented certain new and useful Improvements in and Relating to Filing Appliances, of which the following is a specification.

This invention relates to a filing appliance. 10 For the purpose of illustration, I have, in the accompanying drawings, shown and herein described one form of filing appliance embodying my invention.

Figure 1 is a side elevation of a filing 15 appliance embodying my invention, one side of the casing being removed. Fig. 2 is a bottom plan view of the leaves. Fig. 2^a is a front view of a portion of one of the leaves showing the clamping devices. Fig. 20 3 is a fragmentary sectional view through some of the leaves. Fig. 4 is a fragmentary longitudinal sectional view through the hinge devices. Figs. 5, 6, 7, and 8 are detail views.

25 In the drawings 1 indicates a casing or housing, preferably comprising a desk portion 1^a, a back 1^b, and a base 1^c.

2 indicates a series of leaves supported upon the base 1^c in a manner to permit their 30 detachment therefrom for storing in a vault or other place of safe keeping. The pivotal supporting means for the series of leaves preferably comprise a pair of bearing blocks 1^d upon which the front leaf of the series 35 of leaves rests. Each leaf 2 of the series of leaves is formed from sheet metal, as shown at 2^a, and is preferably provided with end strips 2^b and spacing strips 2^c upon its opposite faces.

40 3 indicates suitable clamping devices for securing papers or paper slips in position against one or both faces of a leaf 2. As it is desirable to support papers or paper slips upon one face only of the frontmost 45 and rearmost leaves of the series of leaves, it will be understood that these two leaves are provided with end strips 2^b and spacing strips 2^c and clamping devices 3 upon their inner faces only.

50 4 indicates tubular members, one carried by each leaf along its lower longitudinal edge, for hingedly connecting the leaves

together, whereby they may be operated from one position to another one by one, or in groups. These hinge members also operate to strengthen the leaves longitudinally. Each tubular member 4 is bent or pressed into a substantially rectangular tube 4^a and provided with two series of longitudinally extending alined bearing loops 4^b, 4^c. The 60 opposite longitudinal free edges of the tube 4^a are preferably bent outwardly laterally and arranged parallel to each other for engagement with the opposite faces of the adjacent leaf 2.

65 4^d indicates rivets for securing the opposite longitudinal edges of the tubes to the adjacent leaf 2. The inner edge of each leaf 2 preferably extends through the adjacent tube into engagement with the inner 70 face of the outer wall of the tube and acts as a brace therefor. As shown in the drawings, the alined bearing loops 4^b, 4^c, of one leaf 2 are arranged alternately with reference to the alined bearing loops 4^b, 4^c, of 75 the adjacent leaves 2, whereby the bearing loops 4^b of each leaf may register with the bearing loops 4^c of an adjacent leaf to receive a pivot device 5.

80 The pivotal devices 5 may extend from end to end of the tubular hinge members. Each device 5 preferably comprises a strip of sheet metal rolled or pressed longitudinally into cylindrical form. This form of pivotal device for the leaf operates to maintain the bearing loops in perfect alinement at all times, thus making the appliance durable and easy to manipulate.

85 As a result of my improvements, a filing appliance of economical construction, light weight, and possessing strength and durability is obtained.

6 indicates a buffer or cushioning device mounted on the back 1^b. This device operates to cushion the leaves 2 when they are 90 returned to normal position. The buffer 6 preferably comprises a pair of telescoping members 6^a, 6^b, and a spring 6^c to press the movable member 6^b of the device outwardly.

6^d indicates a stop for limiting the outward movement of the member 6^b.

7 indicates a guide arm pivotally mounted on the back. This arm operates to move the free ends of the leaves forwardly or rear-

wardly as the latter are operated from one position to another, and vice versa.

7^a indicates a latch carried by the free end of the arm 7. The latch engages the 5 frontmost leaf of the series and locks all of the leaves in a substantially vertical position. In case the clamping devices between some or all of the leaves are filled up with slips to such an extent that some or all of 10 the leaves are somewhat separated from each other when returned to normal position, the buffer 6 will permit the leaves to be pressed backwardly far enough for the latch 7^a to engage the frontmost leaf so that 15 all of the leaves will be locked thereby.

To those skilled in the art of making devices of the class described, many alterations in construction and widely differing embodiments and applications of my invention will suggest themselves, without departing from the spirit and scope thereof. My disclosures and the description herein are purely illustrative, and are not intended to be in any sense limiting.

25 25. What I claim is—

1. In a filing appliance, the combination of a leaf formed from sheet metal and arranged to swing from one position to another, and a tubular member arranged along 30 the hinged or pivotal edge of the leaf and extending from end to end thereof and connected to said leaf along its opposite longitudinal edges.

2. In a filing appliance, the combination 35 of a leaf formed from sheet metal and arranged to swing from one position to another, and a tubular member arranged along the hinged or pivoted edge of the leaf and extending from end to end thereof, the opposite longitudinal edges of the tubular member being arranged parallel to each other, and means for connecting the opposite edges 40 of the tubular member to the leaf.

3. In a filing appliance, the combination 45 of a leaf formed from sheet metal, and a tubular member extending along one longitudinal edge of the leaf, the opposite longitudinal free ends of the tubular member being arranged parallel to each other and secured to the opposite faces of the leaf, and the adjacent edge of the leaf extending through the tubular member into engagement with the inner face of the opposite wall of said member. •

55 4. In a filing appliance, the combination of a leaf formed from sheet metal, tubular hinge members extending along one longitudinal edge of the leaf and formed with two series of alined loops arranged for connection with alined loops of similar hinge members, and the opposite longitudinal free ends of the tubular member being bent or pressed laterally parallel to each other and secured to the opposite faces of the leaf.

65 5. In a filing appliance, the combination

of a series of leaves each formed from sheet metal, tubular hinge members, one for each leaf, extending along one longitudinal edge thereof, and means for pivotally connecting the hinge members together.

70

6. In a filing appliance, the combination of a series of leaves each formed from sheet metal, tubular members formed from sheet metal and provided with alined bearing loops, means for securing each tubular member to an adjacent leaf, and means extending through the alined loops carried by adjoining leaves for pivotally uniting the tubular members together.

75

7. In a filing appliance, the combination 80 of a series of leaves, each formed from sheet metal, tubular hinge members, one for each leaf, extending along one longitudinal edge thereof, the opposite longitudinal free ends of the tubular members being arranged parallel to each other and secured to the opposite faces of an adjacent leaf, and means for pivotally securing the tubular members together.

85

8. In a filing appliance, the combination 90 of a series of leaves, tubular members, one for each leaf and connected thereto and provided with two series of alined bearing loops, the bearing loops of one leaf being arranged alternately relative to the bearing loops of the adjacent leaves, whereby one series of alined loops of a tubular member registers with a series of alined loops of the adjacent tubular member, and means extending through each series of registering loops 100 for pivotally connecting the tubular members together.

95

9. In a filing appliance, the combination 105 of a series of leaves, tubular members, one for each leaf and connected thereto and provided with two series of alined bearing loops, the bearing loops of one leaf being arranged alternately relative to the bearing loops of the adjacent leaves, whereby one series of alined loops of a tubular member registers with a series of alined loops of the adjacent tubular member, and means comprising a strip of sheet metal rolled or pressed into cylindrical form and extending through each series of registering loops for 115 pivotally connecting the tubular members together.

110

10. In a filing appliance, the combination of a series of leaves, each formed from sheet metal, hinge members, each comprising a 120 sheet metal plate pressed or formed into a rectangular tube and provided with two series of alined bearing loops, each series of loops of one hinge member being arranged to register with a series of loops provided 125 in the adjacent hinge member, and means extending through the registering loops for pivotally connecting the hinge members together.

125

11. In a filing appliance, the combination 130

of a series of leaves formed from sheet metal, hinge members, one for each leaf, and comprising a sheet metal plate formed into a rectangular tube and provided with two series of aligned bearing loops, each series of loops of one hinge member being arranged to register with a series of loops provided in the adjacent hinge members, and a cylindrically shaped pivot device extending through

each series of registering loops for pivotally connecting the hinge members together.

In testimony whereof I affix my signature, in the presence of two witnesses.

HARRY J. HICK.
